FUEL INJECTION DEVICE

Lars Olof Hedblom, Detroit, Mich., assignor of
one-half to Gustav A. Carlson, Detroit, Mich.

Application June 6, 1932, Serial No. 615,624

3 Claims. (Cl. 103—153)

The present invention pertains to a novel fuel injection pump designed particularly for the injection of fuel into the cylinder of a Diesel engine, although it is equally useful for similar or related purposes.

The injection pressure stroke on the fuel charge is derived from a cam shaft, and in this connection, the principal object of the invention is to lubricate the operating parts associated with this shaft and also to prevent leakage of fuel into the housing containing the shaft and these parts. With this object in view, the cam shaft is enclosed in a fluid tight casing, and a circulation of lubricating oil is maintained through this casing, the path including a chamber disposed between the casing and the point where the injection stroke is applied to the fuel charge. Thus, two pumping systems are provided, and these are constructed in such a manner that the pressure in the lubricating oil system is greater than that in the fuel system. Inasmuch as the oil circulation system passes between the aforementioned casing and the point where pressure is applied to the fuel charge, there is no possibility of leakage of fuel from this point to the casing.

The cam shaft is operatively connected to the crank shaft of the engine, and in this connection, another object of the invention is to avoid operative performance of the cam-operated pumping mechanism when the engine is running on momentum after the throttling has been closed. To this end, the closing of the throttle effects an adjustment in the pumping mechanism whereby continued rotation of the cam shaft under momentum results in no appreciable pumping action.

The invention is fully disclosed by way of example in the following description and in the accompanying drawings, in which—

Figure 1 is a vertical section of the device;
Fig. 2 is a vertical section in a plane at right angles to the plane of Figure 1;

Fig. 3 is a detail section of a modified construction; and

Fig. 4 is a diagrammatic view illustrating the operation of the device.

Reference to the views will now be made by use of like characters which are employed to designate corresponding parts throughout.

The body or housing of the device comprises a crank case 1 upon which is mounted an upper body portion 2 secured in position by any suitable means such as studs 3. To one of the sides of the crank case 1 is secured a housing 4 for a turbine pump, and after assembly of the pump

in the manner presently to be described, the housing 4 is closed by a lateral cover plate 5. A cam shaft 6 is passed through the case 1 and is accommodated in roller bearings 7 mounted in the sides of the case. Within the case, the shaft 6 is formed with a cam 8 which serves a purpose presently to be described. The shaft 6 is extended as at 9 into the turbine housing 4 and is there equipped with a bladed rotor 10 slidably mounted by means of a pin 11 extending from the hub 10 of the rotor into a slot 12 in the shaft extension 9. A spring 13 surrounding the hub of the rotor bears against the plate 5 urges the rotor against a packing 14 and an interposed thrust bearing 15. A fuel line 16 extends from a suitable source of supply to the interior of the turbine housing 4, and the fuel pumped by the turbine is ultimately delivered and injected into a cylinder.

In the upper part of the section 2 is formed a fuel reservoir 17. A sleeve 18 is passed through the top of the section 2 and through the reservoir 17 to extend a considerable distance towards the crank case 1 as may be seen in Figures 1 and 2. A delivery line 19 extends from the periphery of the turbine housing 4 to the reservoir 17.

The upper end of the reservoir 17 is sealed by a ring 20 clamped by a nut 21 on the exposed portion of the sleeve 18. From the upper end of the sleeve extends a line 22 held by a coupling 23 and leading to an injection nozzle at the cylinder of a Diesel engine in a manner well known in the art and therefore not illustrated here.

A journal shaft 24 is mounted in the bottom of the crank case 1 in parallel relation to the shaft 6, and on the shaft 24 is journaled a curved rocker arm 25 in the form of a frame having its sides straddling the cam 8 in the manner illustrated in Figure 1. The rocker arm carries a roller 26 engageable with the cam 8, and in the normal position shown in Figure 2, the centers of the shaft 6 and roller 26 are preferably in the same horizontal line. The upper end of the rocker arm 25 carries another roller 27, the center of which is normally in a vertical line with the center of the shaft 6.

A horizontal shaft 28 is passed through one of the upper corners of the crank case 1 in parallel relation to the shaft 6 and carries a disk 29 to which is pivotally attached a control or operating arm 30 at an eccentric point 31. The arm 30 has a straight lower edge 32 resting upon the roller 27 and continued downwardly at 32' towards the free extremity of the arm.

On the lower end of the sleeve 18 is screwed another sleeve 33 having a flange 34 bearing up-

wardly against a shoulder 35 formed in the section 2. A plunger 36 is slidably mounted in the lower part of the sleeve 33 and extends upwardly through the sleeve 18 beyond the bottom of the reservoir 17. The lower end of the plunger 36 is rounded at 37 and rests upon the arm 30. The lower end of the plunger is further formed with a spring seat 38 receiving the lower end of a spring 39 which has its upper end bearing against the shoulder 34 to hold the plunger normally in engagement with the arm 30.

At the shoulder 34, ports 40 are drilled through the sleeve 33 and communicate with a chamber 41 formed in the upper section 2. An oil delivery line 42 extends to this chamber preferably from the crank case 1. An oil outlet line 43 also extends from the chamber, returning to the crank case. Beneath the lower end of the sleeve 18, the plunger 36 is formed with an upwardly facing shoulder 44 which constitutes a piston area in drawing oil from the line 42 and discharging it into the line 43 when the plunger oscillates in the manner presently to be described. This pumping unit is made operative by the provision of a check valve 45 in the line 42 and opening in the direction of the chamber 41, and another check valve 46 in the line 43 and opening in the direction of the crank case 1. The valve 46 is backed by a spring 47 adjustable by means of a screw plug 48, whereby the pressure developed in the chamber 46 may be regulated.

In the upper end of the plunger 36 is formed a cavity 49 in which is mounted an upwardly opening poppet valve 50 resting on a spring 51. Ports 52 are drilled through the sleeve 18 at the reservoir 17 to register with ports 53 in the plunger 36 and communicating with the cavity 49 when the plunger is in the lowered position shown in Figures 1 and 2.

40 A plug 54 is mounted in the sleeve 18 at a distance above the upper end of the plunger 36 and has a series of passages 55 drilled therethrough. A poppet valve 56 is slidably mounted in the plug and is adapted to obstruct the passages 55 when in lowered position. A spring 57 bearing upon this valve normally holds it in closed position.

An arm 58 is secured to an end of the shaft 28 exteriorly of the crank case 1 and is suitably linked to the throttle of the engine. A spring 59 secured to an inner wall of the casing 1 and bearing against a pin 60 across the rocker arm 25 holds the roller 26 in constant engagement with the cam 8. When the throttle is closed, the arm 58 and pivot point 31 assume the position shown in Figure 2 and in full lines in Figure 4, and at this time the roller 27 does not ride beyond the straight edge 32'. The center of the journal shaft 24 is displaced about three degrees from the vertical center line of the cam shaft 6, and this relation results in a negligible vertical lift in the arc of the roller 27, so that the plunger 36 is practically stationary after the throttle has been closed. Thus, the turning of the cam shaft 6 under momentum after closing of the throttle causes no significant pumping and injection action although the rocker arm 25 may oscillate a few strokes.

As the throttle is opened, the arm 58 approaches the dotted line position of Figure 4, retracting the pivot point 31 from the axis of the plunger 36 so that the inclined edge 32' of the arm 30 comes into the path of the oscillating roller 27. Consequently, the arm 30 and hence the plunger 36 are oscillated.

75 The function of the turbine pump 10 is merely

to maintain the reservoir 17 filled with fuel oil. An overflow line 61 therefore extends from the reservoir in order to avoid the development of a substantial fluid pressure therein. A transparent sight tube may be inserted in the line 61 so that the flow of oil therethrough may be seen, and the stopping of this flow indicates depletion of the fuel source or some other defect in the mechanism. On replenishment of the fuel supply after depletion, the chamber 17 and connected lines may contain air, and this air may be expelled through a petcock (not shown) inserted in the line 61.

In the fuel pumping operation of the device, the cavity 49 and the space between the plunger 36 and the plug 54 are filled with fuel from the reservoir 17 through the ports 52 and 53. On the upward movement of the plunger, the ports 53 pass out of register with the ports 52, thereby trapping a charge of fuel within the sleeve 18. Continued upward movement ejects this charge of oil through the passages 55, or the head of the valve 50 engages the stem 62 of the valve 56 and opens the latter. At this time, the valve 50 closes against the upper end of the plunger 36, since the spring 57 is preferably stronger than the spring 51. Thus, a charge of fuel is forcibly injected into the line 22 and hence through the nozzle at the cylinder on each revolution of the shaft 6 which is geared to and properly timed with the crank shaft of the engine.

As previously stated, the shoulder 44 of the plunger 36 functions as a piston in a pumping unit embodying also the chamber 41 and the lines 42 and 43. An oil supply line 63 extends into the bottom of the crank case from a suitable supply adapted to maintain a constant level of oil within the crank case. The area of the shoulder 44 is greater than the total area of the upper end of the plunger 36, so that the pressure of lubricating oil developed in the chamber 41 is greater than that developed in the fuel pumping mechanism, whereby the downward leakage from the reservoir 17 of fuel oil towards the crank case is effectively and positively prevented. At the same time, the lubricating oil circulating to the chamber 41 and ports 48 lubricates the contacting surfaces of the plunger 36 and sleeve 33 as well as the contacting surfaces of the end 37, arm 30 and roller 27.

In Figure 3 is illustrated a somewhat modified fuel pumping construction.

A sleeve 18' is passed downwardly into the upper section 2' in substantially the manner previously described and is further locked thereto by a nut 65 bearing upon a shoulder 66 in the section 2'. A sleeve 33' hangs from a shoulder 67 on the lower part of the sleeve 18' and is drawn upwardly against the shoulder 66 by the nut 65. The plunger 36' has two diameters to fit respectively in the sleeves 18' and 36' and to provide clearance 68 in the sleeve 33' for the oil pumping action. In this case, however, the sleeve 33' is formed with ports 69 leading to a cavity 70 in the lower part of the section 2' so that the lubricating oil is returned directly to the crank case rather than through an outside line such as the line 43 of Figure 1. The member 33' has a pressed fit into the member 2', and the member 18' is similarly fitted into the sleeve 33'.

In either embodiment the position of the pivot point 31 is adjusted automatically in accordance with throttle adjustment, and hence there is an automatic adjustment in the length of the arm

30 between the point 31 and the point of contact with the roller 27. Thus, the speed of the plunger is automatically advanced and retarded in keeping with throttle adjustment. It will also 5 be seen that the speed of the plunger is always high in comparison with that of the shaft 6 due to the ratio of more than 2 to 1 in the lever arms comprised in the rocker 25.

It will be understood that the unit illustrated 10 and described herein serves one cylinder of a Diesel engine, and where a plurality of cylinders are provided, it is necessary to provide a corresponding number of units. These units may be built in multiple, and the respective operating 15 cams thereof must be adjusted to operate in proper timed relation with the intended injection interval in each cylinder.

Although specific embodiments of the invention have been illustrated and described, it will 20 be understood that various alterations in the details of construction may be made without departing from the scope of the invention, as indicated by the appended claims.

What I claim is:—

25 1. In combination, a fuel injector housing having two opposed coaxial walled cylinders having a common cylinder head, a hollow insert extending through said cylinders and through said head and having a shoulder thereon for pressure contact with the interior of the head in one of said cylinders, means threaded on each end of said insert for closing the open ends of said cylinders, said insert being of smaller diameter than either of said cylinders and defining two 30 reservoirs therewith, one of said reservoirs having a fuel inlet thereto, the other of said reservoirs having a valved lubricant inlet and outlet, a stepped plunger having a part reciprocable in said hollow insert, and a part reciprocable in one of said means, a walled passageway leading 35 from the lubricant reservoir into the means which receives the said part of the plunger above the step of said plunger, a second walled passageway leading from the fuel reservoir to the interior of said insert and to the interior of said plunger near the top end thereof, a valved outlet 40 from the interior of said plunger, and a valved outlet from said insert above said plunger.

2. A fuel injector housing having a vertical cylindrical bore intermediate the length thereof terminating at each end in coaxial bores of larger diameter, a hollow insert coaxially of said bores having a shoulder thereon for contact with the base of the upper of said bores and threaded at each end, a hollow nut threaded on each end of said insert and bearing against the upper and lower edges of said upper and lower bores respectively, said insert being of smaller diameter 10 than said upper and lower bores and defining reservoirs therewith, said insert and the lower nut comprising a stepped cylinder for a stepped plunger, said plunger having a valved reservoir therein in communication with the top one of 15 said reservoirs and openings through the lower nut from the lower one of said reservoirs to the step of the plunger, a valved outlet from the insert above said valved reservoir, pressure means 20 for feeding fuel to the top one of said reservoirs, and valved lubricant inlet and outlet means for the lower of said reservoirs.

3. A fuel injector housing having a vertical bore intermediate the end thereof opening into an upper and a lower bore of larger diameter, a hollow cylindrical insert having a shoulder intermediate the length thereof for contact with the base of said upper bore, hollow nuts threadable onto each end of said insert for pressure contact with the upper and lower edges of said upper and lower bores respectively, said nuts also imposing pressure contact between the shoulder of said insert and the base of said upper bore, said insert with said upper bore and the nut on the lower end thereof defining two 25 reservoirs, a stepped plunger having a part received in said insert with the stepped part thereof received in the lower nut and comprising a pump for the lower one of said reservoirs, said plunger being hollow and having a valved outlet 30 from the end thereof, walled passageways leading from the upper of said reservoirs into the hollow end of said plunger at a point substantially inwardly of the valved end thereof, and a valved outlet carried by said insert outwardly 35 of the end of said plunger. 40

LARS OLOF HEDBLOM.
